BARNET R. RAPP, OF PHILADELPHIA, PENNSYLVANIA, ASSIGNOR TO HIMSELF, E. LANE, AND J. GORDON MAXWELL, OF SAME PLACE.

Letters Patent No. 94,912, dated September 14, 1869.

IMPROVEMENT IN THILL-COUPINGS.

The Schedule referred to in these Letters Patent and making part of the same.

To all whom it may concern:

Be it known that I, BARNET R. RAPP, of Philadelphia, Pennsylvania, have invented an Improved Carriage-Coupling; and I do hereby declare the following to be a full, clear, and exact description of the same.

My invention consists of a cam-lever hung to a carriage-clip, and arranged for compressing a rubber block to the end of the shaft, thereby preventing the usual disagreeable rattling, and for relieving the said end of the shaft from the pressure of the rubber when the coupling-pin has to be withdrawn.

My invention further consists of the combination of the said cam-lever, an elbow-plate, and the said rubber block, the whole being arranged in respect to the carriage-clip and end of the shaft, substantially as described hereafter.

My invention also consists in combining with the said cam-lever certain arms for retaining the coupling-pin in its place.

In order to enable others skilled in the art to make and use my invention, I will now proceed to describe its construction and operation, reference being had to the accompanying drawing, which forms a part of this specification, and in which—

Figure 1 is a perspective view of my improved carriage-coupling;

Figures 2 and 3, longitudinal sections of the same; and

Figure 4, a transverse section on the line 1-2, fig. 3. Similar letters refer to similar parts throughout the several views.

A represents part of a carriage-axle, to which is adapted the clip B, and to the latter is secured an extension-plate, E, to the outer end of which a cam-lever, F, is hung, by a pin, e, and from the opposite sides of this lever project arms f, in the end of each of which is a recess, j, for a purpose explained hereafter.

From the clip B project the two arms a a, between which fits the metal end N of the shaft, the latter being jointed to the arms by a pin, C.

I is an elbow-plate, the vertical portion of which fits freely between the arms a a, and bears against the clip and extension-plate E, the horizontal portion of the elbow-plate resting on the cam-lever F, which has a recess for receiving a projection or rib on the under side of the said plate; as seen in fig. 4.

H is a block of India rubber, which, when the end of the shaft is in its place, and the cam-lever is elevated, is tightly confined between the elbow-plate and end N of the shaft.

In connecting the shaft to the above-described coupling, the cam-lever is at first depressed to the position

shown in figs. 1 and 2. The end of the shaft is then introduced between the arms a a of the coupling, and the pin C is inserted into its place, after which the cam-lever F is elevated from the position shown in figs. 1 and 2 to that seen in fig. 3. In doing this, the face d of the cam which is furthest from the fulcrum-pin is brought to bear against the elbow-plate I, to elevate the same, and consequently to compress the rubber block H against the end N of the shaft, thereby causing the same to bear tightly against the pin, and thus preventing all disagreeable rattling.

When the cam-lever has been thus elevated, the rubber and elbow-plate are securely retained, laterally by the arms f f, and longitudinally between the clip and portion d² of the lever; at the same time the recessed ends of the arms f f cover the opposite ends of the pin O, which is thus held in its proper position.

A strap, passed through an eye at the outer end of the cam-lever, and through a similar eye, T, on the shaft, and buckled or otherwise connected together at its opposite ends, will prevent the shafts from becoming disengaged from the carriage if the coupling-pin should accidentally break.

While my improved coupling-bolt effectually prevents all rattling of the shafts on the pin, the latter can be readily withdrawn, and the shafts uncoupled, after simply depressing the cam-lever, for by doing this the rubber block is brought to such a position that its pressure against the end of the shaft ceases, while at the same time the pin is uncovered, thereby permitting its ready withdrawal.

It will be understood that my invention can be used to advantage in coupling the pole of a carriage to the axle.

I claim as my invention, and desire to secure by Letters Patent—

1. The shaft, hung at its end N to a stationary pin, C; the block of rubber H, adapted to the rounded end of the shaft, and adjustable to and from the same; and the cam-lever F, bearing with its inner end against a plate, I, beneath the block H, the whole being arranged substantially as described.

2. The arrangement, on the cam-lever F, of the arms f f, all substantially as and for the purpose set forth.

In testimony whereof, I have signed my name to this specification, in the presence of two subscribing witnesses.

BARNET R. RAPP.
